United States Patent Office

Des. 188,356
Patented July 5, 1960

188,356

FILM SPLICER

Frederick Hertzler, St. Clair Shores, Mich., assignor to
Sylvania Electric Products Inc., a corporation of Delaware

Filed Sept. 3, 1959, Ser. No. 57,421

Term of patent 7 years

(Cl. D61—1)

FIG. 1

FIG. 2

FIG. 3

FIG. 4

Figure 1 is a perspective view of a film splicer showing my new design;

Figure 2 is a side elevational view, the opposite side being substantially a mirror image thereof;

Figure 3 is a front elevational view thereof; and

Figure 4 is a perspective view of the film splicer in an open position.

I claim:

The ornamental design for a film splicer, substantially as shown and described.
